US0D1012601S

(12) United States Design Patent (10) Patent No.: US D1,012,601 S
(45) Date of Patent: * Jan. 30, 2024

(54) FOOD PROCESSOR

(71) Applicant: Smart Product Concepts Limited,
Kowloon (HK)

(72) Inventor: Mark Fung, Tseung Kwan O (HK)

(73) Assignee: Smart Product Concepts Limited,
Kowloon (HK)

() Term: 15 Years

(21) Appl. No.: 29/832,014

(22) Filed: Mar. 24, 2022

(30) Foreign Application Priority Data

Jan. 14, 2022 (EM) 008829824-0001
